(57) **CLAIM**

The ornamental design for an aspirator base console, as shown and described.

DESCRIPTION

FIG. 1 is a top, front, right side perspective view of an aspirator base console, showing my new design;

FIG. 2 is a top, front, right side perspective of an aspirator base console;

FIG. 3 is a top plan view thereof;

FIG. 4 is a front elevational view thereof;

FIG. 5 is a right side elevational view thereof; and,

FIG. 6 is a left side left side elevational view thereof.

The broken lines shown in the drawings are for environmental purposes only and form no part of the claimed design.
